UNITED STATES PATENT OFFICE.

GEORGE M. JOHNSTON, OF VANDERGRIFT, PENNSYLVANIA.

METALLIC-SHEET-SEPARATING MACHINE.

1,119,611.

Specification of Letters Patent.

Patented Dec. 1, 1914.

Application filed March 28, 1914. Serial No. 827,925.

To all whom it may concern:

Be it known that I, GEORGE M. JOHNSTON, a citizen of the United States of America, residing at Vandergrift, in the county of 5 Westmoreland and State of Pennsylvania, have invented certain new and useful Improvements in Metallic-Sheet-Separating Machines, of which the following is a specification, reference being had therein to the 10 accompanying drawing.

This invention relates to metallic sheet separating machines and has for its object to provide means, in a manner as hereinafter set forth, for separating a pair of metallic sheets which have been secured together during the rolling operation, and to overcome the necessity of manually separating the sheets, which is now in general vogue, and which requires considerable time.

20 Further objects of the invention are to provide a sheet separating machine which is simple in its construction and arrangement, strong, durable, efficient and convenient in its use, readily set up and comparatively inexpensive to manufacture.

With the foregoing and other objects in view the invention consists of the novel construction, combination and arrangement of parts as hereinafter more fully described 25 and illustrated in the accompanying drawings, wherein is shown an embodiment of the invention, but it is to be understood that changes, variations and modifications can be restorted to which come within the scope of 30 the claims hereunto appended.

In describing the invention in detail, reference is had to the accompanying drawings wherein like reference characters denote corresponding parts throughout the several 40 views, and in which:

Figure 1 is a front elevation of a metallic sheet separating machine in accordance with this invention; Fig. 2 is a section on line X—X Fig. 1, looking in the direction of the 45 arrow; Fig. 3 is a view looking toward one end of the separating rolls, these latter being broken away; Fig. 4 is a vertical sectional view, broken away, of the separating rolls; Fig. 5 is a sectional plan of one-half of one 50 of the separating rolls, the roll being broken away, and Fig. 6 is a detail of a modified form illustrating a bearing for the lugs or shafts for the clamping members.

Referring to the drawings in detail, 6 55 notes the base and 7—8 the sides of the housing, and journaled in the sides 7—8 is an

upper and a lower separating roll shaft, the latter being intermittently rotated. The upper shaft is indicated at 9, and the lower shaft at 10. The shaft 9 projects from the 60 side 7 and carries a gear 11, and the shaft 10 projects from the side 7 and carries a gear 12, which meshes with the gear 11. The shaft 10 is connected to a prime mover, not shown, for driving it intermittently, and 65 motion is transmitted to the shaft 10; the shaft 9 is also driven owing to the gear connections 11—12, but the shaft 9 will revolve in an opposite direction with respect to the direction of the revolution of the shaft 10. 70

Fixedly secured to the shaft 9 is an upper separating rolls 13, and fixedly secured to the shaft 10 is a lower separating roll 14. The rolls 13—14 are arranged in parallelism, and as the rolls are constructed alike, 75 but one will be described, as the description of one applies to the other.

Each of the separating rolls has its body portion formed with a longitudinally extending V-shaped pocket 15, of less length 80 than the length of the body of the roll, and the ends of the pocket 15 are arranged inwardly with respect to the ends of the body of the roll. Each of the rolls is furthermore provided with a longitudinally extending 85 slot 16 which opens into the pocket 15, and is of less width than the mouth of the pocket, the mouth of the pocket being of greater width than the bottom of the pocket. The slot 16 provides what may be termed a pair 90 of oppositely disposed shoulders 17—18, and each of said shoulders are rounded and extend the length of their respective pocket 15; in fact, the shoulders 17—18 are formed from portions of the top wall of the pocket 95 15. When the rolls 13—14 are set up, the pockets 15 extend in opposite directions with respect to each other, and the slot 16 of one roll opposes the slot 16 of the other roll.

Arranged within each of the pockets 15, and mounted against the shoulders 17—18 is a pair of oppositely disposed clamping members 19—20, and each of which is of a length equal to the length of its respective 105 pocket. One end of each of the clamping members is provided with a lug 21 which is seated in its respective roll, and the other end of each of said members has fixed thereto a stub shaft 22, which projects from the 110 roll as at 23 and carries a toothed quadrant. The quadrants carried by the shafts 22 of

the members 19 are indicated at 24, and the quadrants carried by the shafts 22 of the members 20 are indicated at 25. The quadrants 24 are oppositely disposed with respect to the quadrants 25, and said quadrants 24 permanently mesh with the quadrants 25. The normal position of the clamping members carried by the roll 13 is upwardly at an angle with respect to their quadrants, and the normal position of the clamping members carried by the roll 14 is downwardly at an angle with respect to their quadrants.

Each of the quadrants 24 is provided with a pair of apertured lugs 26, and to one pair of lugs 26 is pivoted a link 27, which is pivotally attached to a pair of lugs 28, carried by a sliding collar 29, mounted upon the shaft 9; and the other pair of lugs 26, has pivotally connected thereto a link 30, the latter being pivotally connected to a pair of lugs 31, carried by a shiftable collar 32, mounted upon the shaft 10. Each of the collars 29 and 32 is provided with a peripheral groove 33, and arranged in each of said grooves is a strap 34, and the said straps 34 have connected thereto a vertically disposed coupling member 35, having a lengthwise extending slot 36.

Carried by the inner face of the side 8 is a bracket 37, in which is pivotally connected a yoke-shaped shifting member 38; the latter extends through the slot 36. The member 38 is provided with a crank arm 39, having pivotally connected therewith the upper end of a pulling rod 40, the latter having its lower end pivotally connected as at 41, to a spring controlled pivoted foot-tread 42. The normal position of the member 38 is at an upward inclination whereby when said rod 40 is pulled downwardly, the action of the member 38 will be such as to shift the coupling member 35 toward the rolls, and said member 35 will carry the collars 29 and 32 therewith. As the collars 29 and 32 are moved toward the rolls 13 and 14, the links 27-30 will be simultaneously actuated, moving the quadrant 24 carried by the roll 13 downwardly, and the quadrant 24 carried by the roll 13 upwardly, and by such movement of the quadrants 24, a like movement will be imparted to the quadrants 25, owing to the fact that the quadrants 24 mesh with the quadrants 25. When the quadrants carried by the roll 13 are moved downwardly, the clamping members within said roll are also moved downwardly, and when the quadrants of the roll 14 are moved upwardly, the clamping members within said roll 14 are also moved upwardly, or in other words when the quadrants are shifted by moving the collars 29 and 32 toward the rolls 13-14, the clamping members of each roll are shifted toward each other. The clamping members of each

roll are utilized for connecting the ends of the metal sheet therewith, as indicated at 43-44, whereby when the rolls 13-14 revolve, a pair of secured sheets, as indicated at 45, are separated. The ends 43-44 of the pair of secured sheets are first separated by hand and extended into the pockets so that they can be engaged by the clamping members when the collars 29-32 are shifted toward the rolls 13-14. The length of the sheets to be separated is slightly less than the circumference of the separating rolls. The clamping members are maintained in engagement with the ends of the sheets 43-44, as long as pressure is applied to the foot-tread 42. When pressure is released from the foot-tread 42, the spring 46 restores said tread 42 to normal position, and during such action the collars 29-32 are shifted away from the rolls 13-14 due to the action of the member 38 with respect to the coupling member 35.

In Fig. 6 of the drawings, a modified construction is set up relative to the manner of supporting the lugs or shafts of the clamping members 19 and 20. Each of the rolls, which is indicated at 51 is provided with a pocket 48, which corresponds to the pocket 15, but the said pocket 48 is of a length equal to the length of its respective roll. Each of the rolls 51 is provided at each end with seats 52, upon which are mounted flanges 49, and the bearing plates 46 which are seated in the pockets at the ends thereof are flush with the ends of their respective roll 51. The flanges 49 are fixedly secured to their respective roll 51 by holdfast devices 50. The bearing plates 46 are provided with openings 47, in which are seated the lugs or shafts 21^a for the clamping members 19 and 20. The lugs or shafts 21^a at one end of the clamping members are flush with one end of the roll 51 and the lugs or shafts 21^a at the other ends of the clamping members are projected and have the quadrants 21 and 25 mounted therein. The bearing plates 46 are flush with the ends of the rolls and the top edges of the bearing plates 46, as well as the top edges of the flanges 49 forming a continuation of the periphery of the roll 51.

What I claim is:—

1. A sheet separating machine comprising a pair of rolls revoluble in opposite directions and each provided with a longitudinally extending pocket adapted to have the end of a metal sheet project thereinto, means arranged in each of said pockets and adapted to engage the end of a sheet for clamping said end to the roll, and means for shifting said clamping means to and from operative engagement with respect to the ends of said sheets.

2. A sheet separating machine comprising a pair of rolls revoluble in opposite directions with respect to each other and each

provided with a longitudinally extending pocket adapted to have one end of one sheet of the pair of secured sheets extend thereinto, means for clamping said ends to said rolls whereby when the rolls are revolved, the sheets will be separated, means carried by the rolls for shifting said clamping means to and from operative engagement with the ends of said sheets, and means for simultaneously operating said shifting means to simultaneously position the clamping means carried by said rolls with respect to said ends of said sheets.

3. A sheet separating machine comprising a pair of rolls revoluble in opposite directions with respect to each other and each provided with a longitudinally extending pocket adapted to have one end of one sheet of the pair of secured sheets extend there-

into, means for clamping said ends to said rolls whereby when the rolls are revolved, the sheets will be separated, means carried by the rolls for shifting said clamping means to and from operative engagement with the ends of said sheets, operating means carried by the shafts of said rolls and connected with said shifting means for simultaneously operating them to cause the simultaneous positioning of said clamping means with respect to the ends of said sheets, and actuating means for said operating means.

In testimony whereof I affix my signature in the presence of two witnesses.

GEORGE M. JOHNSTON.
